(57) **CLAIM**

The ornamental design for a power supply adapter, as shown and described.

DESCRIPTION

FIG. 1 is a perspective view of a power supply adapter showing a new design;

FIG. 2 is a front elevational view thereof;

FIG. 3 is a left side elevational view thereof;

FIG. 4 is a right side elevational view thereof; and,

FIG. 5 is a top plan view thereof.

The back view is a mirror image of the front view, and the bottom plan view is a mirror image of the top plan view.

1 Claim, 1 Drawing Sheet

Matter enclosed in heavy brackets [ ] appears in the original patent but forms no part of this reissue; matter printed in italics indicates the additions made by reissue.
